SPRING CONTROLLED SPARK DEVICE FOR
ENGINES

Vernon G. Smith, Willows, Calif.

Application June 6, 1936, Serial No. 83,871

8 Claims. (Cl. 123—148)

This invention relates to new and useful improvements in a spring controlled spark device for engines.

The invention has for an object the construction of a spark device which is adapted to be mounted upon the combustion chamber of an engine and which automatically operates when the compression within the combustion chamber is a pre-determined amount.

Specifically, the invention proposes arranging a high tension terminal on the stem of a piston head which is spring loaded and associated with an arrangement to cause the spark when the piston reaches a pre-determined position.

Still further the invention proposes an adjustment for limiting the motion of the piston so that the distance between certain breaker points controlling the spark may be adjusted.

Another one of the objects of the invention resides in a mechanism for adjusting the spring tension so that the spark may be produced at desired retarded or advanced positions relative to the power piston position within the combustion chamber. Of course, this is controlled merely by the spring pressure.

Another one of the objects of this invention is the provision of a diaphragm associated with the piston head to insure against the passage of gas from the interior of the combustion chamber.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a fragmentary side elevational view of an engine equipped with several spring controlled spark devices according to this invention.

Fig. 2 is a vertical sectional view taken on the line 2—2 of Fig. 1.

Fig. 3 is a fragmentary enlarged detailed view of certain parts shown in Fig. 1.

Fig. 4 is an end elevational view of Fig. 3 looking from the right hand side.

Fig. 5 is a plan view of a certain disc used in the device.

The spring controlled spark device, according to this invention, is adapted to be mounted upon the end wall 10' of the combustion chamber 10 of an internal combustion engine. A piston 11 is shown within the combustion chamber 10 in

its high compression position, and in which position the spark is desired. For this reason Fig. 2 shows the spark device in the operative position with the spark "shooting".

The spark device includes a bushing 12 which is mounted through the inner wall 10' of the combustion chamber 10 and is formed with an internal seat 12a. An annular member 13 is adjustably mounted on the bushing 12 and has an opposed internal seat 13a. A hollow body 14 is mounted on an annular member 13. A piston head 14' is slidable between the seats 12a and 13a and engages the side walls of the bushing 12. An insulation stem 15 projects from the piston head 14' and extends through the hollow body 14. The high tension terminal 16 is mounted on the stem 15 and extends through the head 14' and cooperates with grounded terminals 17 mounted on the head 14'. A disc 18 is slidably mounted upon the stem 15.

A resilient means 19 acts between the disc 18 and indirectly against the piston head 14' for urging the piston inwards. A means is provided for holding the disc 18 in various adjusted positions to tension the resilient means. A breaker point 20 is mounted upon the terminal 16 and in a lowered position of the piston cooperates with a grounded breaker point 21 upon the body 14.

A diaphragm 22 is slightly spaced from the outer end of the piston 14' and is clamped at its edges between the body 14 and the annular member 13. At its center this diaphragm is attached to the stem 15 by engaging between collars 23 and 24 mounted on the stem 15.

The bushing 12 is formed with external threads 35 which threadedly engage internal threads upon the annular member 13. It is thus possible to screw these parts together or apart to desired distances and so control the amplitude of motion of the piston head 14'. Thus the gap between the breaker points 20 and 21 may be controlled. The annular member 13 is formed with external threads upon which internal threads from the lower portion of the hollow body 14 threadedly engage. It is between these portions 40 that the edges of the diaphragm 22 are clamped. The center portion of this diaphragm is capable of moving sufficiently so as not to interfere with the free motion of the piston 14'.

The hollow body 14 is provided with a pair 50 of diametrically opposite longitudinal slots 25 into which pins 26 from opposite sides of the disc 18 engage. These pins engage against a pair of arms 27 which are pivotally mounted at one of their ends on a lug 28 on one side of the body 55

14. These arms 27 extend upwards and at the top ends are formed with slots 29. Bushings 30 are disposed between the upper ends of the arms 27 and have projecting pegs 31 engaging 5 into the slots 29. These bushings 30 threadedly engage on threaded adjustment rods, 31, 32, 33, etc., as the case may be, one bushing being upon each of the rods. Certain of these rods are hollow so that the rods may pass through each 10 other.

The rods 31, 32, and 33 are arranged coaxially on each other and are rotatively supported in standards 34 and 35 mounted upon the body 10a of a combustion engine. The rod 31 is provided 15 with a head 31' by which it may be manually adjusted. The rod 32 is provided with a head 32' and the rod 33 with a head 33'. These various heads may be turned to cause one or the other of the bushings 30 to move along the rods. 20 A change in the position of the bushings will add or subtract pressure from the springs 19. Thus, if the pins 26 against which the rods 27 engage, are forced downwards, the disc 18 will be correspondingly moved and the spring 19 will 25 be compressed, and vice versa, this pressure may be relieved from the spring.

Since it is the springs 19 which control the timing of the breaker points 20 and 21 it is possible to advance or retard the spark by tension changes on the springs. The pressure within 30 each combustion cylinder 10 is assumed to be constant for each position of the power piston, and consequently a change in the tension of the spring controls the timing of the breaker points 35 20 and 21. A live lead 38 is connected with the high tension terminal 16.

The operation of the device is as follows: When the piston 11 reaches the end of its compression stroke, the pressure of the gas within the combustion chamber will be sufficient to raise the piston 14, and consequently the stem 15 will 40 move upwards and the circuit will be broken between the contacts 20 and 21. Heretofore, the high tension lead 38 was grounded by the contact 21, but now the current is forced through 45 the terminal 16, and sparks will jump across the terminals 17. The gas will be ignited in the combustion chamber and power will be delivered to the power piston 15.

50 The distance to which the breaker points 20 and 21 open may be controlled by adjusting the bushing 12 relative to the annular member 13. The rods 31, 32, 33 may be individually adjusted to 55 adjust the pressures of the springs 19 which in turn control the timing of the breaker points 20 and 21.

While I have illustrated and described the preferred embodiment of my invention, it is to be understood that I do not limit myself to the 60 precise constructions herein disclosed and the right is reserved to all changes and modifications coming within the scope of the invention as defined in the appended claims.

Having thus described my invention, what I 65 claim as new, and desire to secure by United States Letters Patent is:—

1. In combination with the chamber of a combustion engine, a bushing mounted through the inner end wall of said combustion chamber and 70 having an internal seat, an annular member adjustably mounted on said bushing and having an opposed internal seat, a hollow body mounted on said annular member, a piston head slidably mounted between said seats, an insulation stem 75 projecting from said head and extending through

said body, a high tension terminal mounted through said stem and coacting with a grounded terminal on said head, a disc slidable on said stem, resilient means acting between said disc and said head, means for holding said disc in fixed adjusted positions to tension said resilient means, and a contact member mounted on said terminal and in the lower position of said piston head engaging a grounded contact. 5

2. In combination with the chamber of a combustion engine, a bushing mounted through the inner end wall of said combustion chamber and having an internal seat, an annular member adjustably mounted on said bushing and having an opposed internal seat, a hollow body 15 mounted on said annular member, a piston head slidably mounted between said seats, an insulation stem projecting from said head and extending through said body, a high tension terminal mounted through said stem and coacting with a grounded terminal on said head, a disc slidable on said stem, resilient means acting between said disc and said head, means for holding said disc in fixed adjusted positions to tension said resilient means, and a contact member 20 mounted on said terminal and in the lower position of said piston head engaging a grounded contact, and a diaphragm spaced from the end of said piston head and clamped at its edges between said body and annular member and fixed 25 at its center on said stem.

3. In combination with the chamber of a combustion engine, a bushing mounted through the inner end wall of said combustion chamber and having an internal seat, an annular member adjustably mounted on said bushing and having an opposed internal seat, a hollow body mounted on said annular member, a piston head slidably mounted between said seats, an insulation stem projecting from said head and extending through 40 said body, a high tension terminal mounted through said stem and coacting with a grounded terminal on said head, a disc slidable on said stem, resilient means acting between said disc and said head, means for holding said disc in 45 fixed adjusted positions to tension said resilient means, and a contact member mounted on said terminal and in the lower position of said piston head engaging a grounded contact, said annular member threadedly engaging said bushing 50 whereby these parts are adjustably connected.

4. In combination with the chamber of a combustion engine, a bushing mounted through the inner end wall of said combustion chamber and having an internal seat, an annular member adjustably mounted on said bushing and having an opposed internal seat, a hollow body mounted on said annular member, a piston head slidably mounted between said seats, an insulation stem projecting from said head and extending through 60 said body, a high tension terminal mounted through said stem and coacting with a grounded terminal on said head, a disc slidable on said stem, resilient means acting between said disc and said head, means for holding said disc in fixed 65 adjusted positions to tension said resilient means, and a contact member mounted on said terminal and in the lower position of said piston head engaging a grounded contact, said piston head having its sides engaging the walls of said 70 bushing.

5. In combination with the chamber of a combustion engine, a bushing mounted through the inner end wall of said combustion chamber and having an internal seat, an annular member ad- 75

- justably mounted on said bushing and having an opposed internal seat, a hollow body mounted on said annular member, a piston head slidably mounted between said seats, an insulation stem 5 projecting from said head and extending through said body, a high tension terminal mounted through said stem and coacting with a grounded terminal on said head, a disc slideable on said stem, resilient means acting between said disc and said head, means for holding said disc in fixed adjusted positions to tension said resilient means, and a contact member mounted on said terminal and in the lower position of said piston head engaging a grounded contact, said disc 10 having pins projecting through slots in said hollow body, arms engaging said pins, and means for holding said arms in various positions to control the tension of said resilient means.
6. In combination with the chamber of a combustion engine, a bushing mounted through the inner end wall of said combustion chamber and having an internal seat, an annular member adjustably mounted on said bushing and having an opposed internal seat, a hollow body mounted 15 on said annular member, a piston head slidably mounted between said seats, an insulation stem projecting from said head and extending through said body, a high tension terminal mounted through said stem and coacting with a grounded terminal on said head, a disc slideable on said stem, resilient means acting between said disc and said head, means for holding said disc in fixed adjusted positions to tension said resilient means, and a contact member mounted on said terminal and in the lower position of said piston head engaging a grounded contact, said resilient means comprising a spring acting against said disc and coaxially mounted on said stem.
8. In combination with the chamber of a combustion engine, a bushing mounted through the inner end wall of said combustion chamber and 20 having an internal seat, an annular member adjustably mounted on said bushing and having an opposed internal seat, a hollow body mounted on said annular member, a piston head slidably mounted between said seats, an insulation stem 25 projecting from said head and extending through said body, a high tension terminal mounted through said stem and coacting with a grounded terminal on said head, a disc slideable on said stem, resilient means acting between said disc and said head, means for holding said disc in fixed adjusted positions to tension said resilient means, and a contact member mounted on said terminal and in the lower position of said piston head engaging a grounded contact, said disc 30 having pins projecting through slots in said hollow body, arms engaging said pins, and means for holding said arms in various positions to control the tension of said resilient means, including a collar associated with the arms and 35 threadedly engaging an adjustment rod, said rod being rotatively supported.
7. In combination with the chamber of a combustion engine, a bushing mounted through the inner end wall of said combustion chamber and 40
